UNITED STATES PATENT OFFICE.

OWEN H. JONES, OF HARTFORD, CONNECTICUT.

FLOAT-ROD FOR FLUSH-TANKS.

SPECIFICATION forming part of Letters Patent No. 715,386, dated December 9, 1902.

Application filed April 14, 1902. Serial No. 102,730. (No model.)

To all whom it may concern:

Be it known that I, OWEN H. JONES, a citizen of the United States, and a resident of Hartford, in the county of Hartford and State 5 of Connecticut, have invented certain new and useful Improvements in Float-Rods for Flush-Tanks, of which the following is a specification.

My invention relates to the class of devices 10 used for holding and supporting a float in a flush-tank or like receptacle; and the object of my invention is to provide a device of this class that shall be extremely simple and cheap in construction, effective in operation, and 15 durable, and with little liability to get out of repair. A device by means of which these objects may be attained is illustrated in the accompanying drawings, in which—

Figure 1 represents in side elevation a valve 20 with a float-rod embodying my invention attached thereto. Fig. 2 is a top view of the outer end of the rod with a float attached therein. Fig. 3 is a view in section through the float and outer end of the rod.

In the accompanying drawings the letter *a* 25 denotes a valve that is adapted to be supported in connection with a flush-tank or like part and which controls the flow of water into said tank in a manner well known in this 30 class of devices, the tank, for this reason, not being illustrated herein. A float-rod *b* is connected to this valve and through the medium of the float-support on the outer end of the rod controls the movement of the valve 35 through the rise and fall of the water within the tank and on which the float is supported.

In devices of this class prior to my invention objections have been encountered in the construction of means for supporting the float.

40 In many instances arms are secured in the base, as by means of interengaging screw-threads, and these arms work loose and allow the float to be disengaged. In other forms of construction clamps operated by screws and 45 like means are employed, and these become inoperative from the action of different ingredients contained in the water.

50 My improvements relate especially to the construction of the float-rod and to the means for supporting the float thereon.

In embodying my invention I construct the float-rod and the means for holding the float at the outer end thereof of a single piece of

metal. The outer end *c* of the rod is bent at an angle to the body part and in the form of 55 a portion of a circle, this bent portion comprising more than half a circle. This holder *c* is provided with sufficient spring action to allow the float *d* to be sprung into place in the holder, where it is held firmly by the 60 spring action of the holder. It will be noted that the rod is substantially straight as to its main body portion and that the holding-loop is formed at the extremity of the straight portion, so that it is possible to remove or insert 65 the float *d* without such undue springing of the loop as will impair its holding qualities. In other words, there is an absolutely open loop formed by bending the outer end of the rod into a semicircle. The float *d* is provided 70 with a cylindrical groove *e*, in which the holder is located, this groove conforming to the outline of the holder and preventing what may be termed "lateral displacement" of the float with respect to the holder. 75

It is obvious that the invention may be embodied in other forms than that herein shown and described and yet come within the scope of the invention, and I do not intend to limit myself to the precise construction of device 80 herein shown, as any float-rod composed of a single piece of metal having on its outer end a single spring-holding arm grasping the float will come within the scope of the invention.

What I claim as my invention, and desire 85 to secure by Letters Patent, is—

1. In combination with a valve or like part, a float-rod connected therewith and comprising a single piece of metal including at its outer end a single spring-holding loop grasping the 90 float and open on one side, whereby the float may be inserted or removed, and the float.

2. In combination with a valve or like part, a float-rod connected therewith and consisting of a single piece of metal including at its outer extremity an offset portion comprising 95 a spring-holding loop adapted to grasp and hold a float, said offset portion being wholly beyond the main body portion of the rod, and a float having a groove adapted to receive the 100 holder.

OWEN H. JONES.
